Attorneys.

Patented Apr. 17, 1928.

UNITED STATES PATENT OFFICE.

JOSEPH P. COLGROVE, OF BUFFALO, NEW YORK.

RAZOR-BLADE HOLDER.

Application filed January 14, 1925. Serial No. 2,423.

This invention relates to a holder for safety razor blades of any standard type, by which a cutting tool is produced appropriate for trimming purposes of various kinds.

5 The object of the invention is to provide a simple, compact and inexpensive holder of this character which securely locks the blade in place and which is so constructed and organized that it can be easily and readily assembled and dismembered in the 10 act of applying and removing the blade.

In the accompanying drawings:

Figure 1 is a perspective view of the improved holder. Figure 2 is an enlarged central longitudinal section thereof. Figures 15 3, 4, 5 and 6 are detached perspective views of the various parts of the holder.

Similar characters of reference indicate corresponding parts throughout the several 20 views.

In the preferred embodiment of the holder shown in the drawings, the same comprises two substantially flat bars or handle sections 10, 11 which may be in the form of metal 25 stampings or otherwise constructed, and which are superposed one on the other for detachably receiving between their front ends a standard type of safety razor blade 12 or similar cutting tool. The latter is 30 adapted to be reliably clamped between the opposing faces of the handle-sections, the upper section 10 being somewhat longer and overhanging the front end of the companion lower section 11, while the rear end of the latter extends a suitable distance beyond the 35 corresponding end of said upper section, as shown in Figs. 1 and 2.

For the purpose of clamping the front ends or head portions of the handle-sections 40 10 and 11 to each other with the blade 12 between them, they are provided near their front ends and substantially centrally thereof with offset lugs or projections 13, 14, respectively, which are preferably hook-shaped 45 and extend lengthwise of the sections. As shown in Figs. 2, 3 and 4, the lug 13 of the section 10 is offset in one direction or downwardly and faces forwardly while the lug 14 of the companion section 11 is offset in the opposite direction or upwardly and faces rearwardly. Said upper section is provided in rear of its clamping lug with an opening 15 with which the lug 14 of the lower handle section is adapted to interlock in the assembled position of the parts, 50 said lugs 14 overlapping the rear edge of

this opening to prevent relative longitudinal displacement of the sections in one direction. The razor blade is provided with the customary openings 16 which are adapted to 60 interlock with the lugs of the handle-sections, the rear portion of the blade being clamped between the opposing faces of the sections and its remaining portion lying flatly against the underside of the upper section 65 10 with the lug of the latter overlapping the front edge of the corresponding blade opening. By this construction and arrangement of parts, the razor blade is rigidly 70 and reliably clamped between the handle-sections, being effectually held against both lateral and longitudinal displacement relative to the sections.

The clamping lugs, 13, 14 may be formed by slitting the sections and then punching 75 the resulting tongues in opposite directions.

To prevent the rear portions of the handle-sections 10, 11 from shifting laterally relatively to each other, one of them is preferably provided with a centering lug 17 arranged to interlock with a corresponding opening 18 in the other section.

A clamping disk 19 is rotatably mounted on the projected rear end of the handle-section 11 and has an upwardly and outwardly offset locking lip 20 arranged to overlap the opposing upper side of the handle-section 10 to lock the rear ends of the sections together. This locking lip also constitutes a finger-piece for conveniently turning the clamping disk into and out of its locked position. In the locked position of this disk, the handle-sections are not only held against separation, but they are at the same time held against shifting lengthwise 95 relative to each other in a rearward direction by the abrupt edge of the disk abutting against the opposing abrupt end of the handle-section 10. Shifting of the sections in the reverse direction is prevented by the rear end of the opening 15 in the upper section bearing against the vertical portion of the corresponding lug 14 of the lower section, 100 as shown in Fig. 2.

In removing the blade from this improved holder, the clamping disk 19 is first turned to move its lip 20 out of locked position, after which the upper handle-section 10 is lifted slightly to disengage the centering lug 17 from its corresponding opening 18. The upper section is then shifted rearward relatively to the companion lower section 11 105

to permit the withdrawal of the lug 14 of the latter from the opening 15 in said upper section and the alining blade-opening. Having thus separated the handle-sections, the 5 blade can now be easily removed from the upper section lug 13.

In applying the blade to the holder the same is locked and clamped between the handle-sections by performing these acts in the 10 reverse order, after which the clamping disk 19 is turned to bring its lip 20 into locked position.

This improved holder is manifestly simple and durable in construction, it holds the 15 blade tightly to cut tough as well as other materials, its parts are so constructed as to permit the ready application and removal of the blade, and it can be manufactured at a moderate cost. Its thin, flat construction 20 makes it light and compact and renders it especially suitable for mailing. It has the further advantage of positively locking the bars against longitudinal displacement on each other, holding their connecting hooks and openings in proper engagement 25 without depending on the user's grasp of the handles for that purpose.

I claim as my invention:—

1. A blade-holder, comprising a pair of 30 separable bars movable lengthwise relatively

to each other and each having a head-portion, and a handle-portion, the head-portion of one bar having a forwardly-facing hook and that of the other bar having a rearwardly-facing hook, the latter 35 interlocking with an opening in the other bar, the bar which carries the first-named hook extending beyond the front end of the other bar while the latter shorter bar is adapted to clamp the blade between itself 40 and the longer bar, and means for holding said bars against relative longitudinal displacement.

2. A blade-holder comprising a pair of 45 separable bars movable lengthwise relatively to each other and each having a head-portion and a handle-portion, said head-portion having mutually-interlocking members which are engaged and disengaged by longitudinal movement of one bar on the other, and means for holding said bars against relative longitudinal displacement, consisting of a rotary clamping disk mounted on one 50 of said bars and having an abrupt edge arranged to bear against the abrupt rear end of the other bar, said disk having a lip which overlaps the last named bar in the normal position of the disk.

JOSEPH P. COLGROVE.
